UNITED STATES PATENT OFFICE.

JOHN THOMAS, OF WINNIPEG, MANITOBA, CANADA, ASSIGNOR OF ONE-THIRD TO
JOSEPH HINK AND ONE-THIRD TO LAWRENCE HINK, BOTH OF WINNIPEG, CANADA.

SAW.

1,056,857.

Specification of Letters Patent. Patented Mar. 25, 1913.

Application filed December 13, 1911. Serial No. 665,445.

To all whom it may concern:

Be it known that I, JOHN THOMAS, of the city of Winnipeg, in the Province of Manitoba, Canada, have invented certain new and useful Improvements in Saws, of which the following is the specification.

My invention relates to an improved saw, especially hand saws, and the object of the invention is to provide a hand operated rotary saw which is self feeding and which can be adjusted to make parallel cuts in the one operation, the construction being such that if necessary single cuts can be made by removing certain of the parts.

With the above objects in view the invention consists essentially in the arrangement and construction of parts hereinafter more particularly described and later pointed out in the appended claim.

Figure 1 is a side elevation of the complete device, part being broken away to expose construction. Fig. 2 is a plan view of the same. Fig. 3 is a vertical sectional view, the section being taken in the plane denoted by the line X X', Fig. 1. Fig. 4 is a vertical sectional view through the saw frame, the section being taken in the plane denoted by the line Y Y', Fig. 1. Fig. 5 is a vertical sectional view through the saw, the section being taken in the plane denoted by the line Z Z', Fig. 3. Fig. 6 is a vertical sectional view through the frame, the section being taken in the plane denoted by the line T T', Fig. 1.

In the drawing like characters of reference indicate corresponding parts in each figure.

1 represents the saw frame which comprises a handle 2 supplied with a suitable hand grip 3 and having the center thereof slotted or cut away at 4 and a slidtable bar 5 received within the slot and retained therein by suitably located side pieces 6 and 7. The handle carries a spring catch piece 8 which passes upwardly through an opening 9 reserved in the handle and engages with the under side of the bar which is toothed at 10. One can set the bar in any desired position by withdrawing the catch piece and moving it backwardly or forwardly as the case may be and then releasing the catch piece to engage with one or other of the teeth. The bar is supplied with a lateral extension 11 which carries a stub axle 12 on

which I have mounted a rotatable fly wheel 13 which carries a chain wheel 14, the chain wheel being fastened to the fly wheel by suitable bolts 15.

16 is a gripping piece supplied on the fly wheel whereby it can be readily turned. 60

17 is a rod permanently set at 18 within the handle and extending forwardly centrally within the slot and into the bar 5, which bar is supplied with an opening 19 to receive it slidably. A spiral spring 20 65 encircles the rod and bears at the ends against the end of the slot and the rear end of the bar thereby causing the handle 3 to move in a direction opposite from the saw blades 29 and 34, when the latch 8 is out of 70 engagement with the bar 5.

21 is a cross plate located at the forward end of the handle and closing the end of the slot.

22 is a cross shaft mounted rotatably in 75 the forward end of the bar and having one end thereof threaded at 23 and a squared enlargement formed thereon at 24 adjoining the threaded end.

25 is a washer on the shaft and located 80 at one side of the bar, and 26 is a removable collar also located on the shaft and appearing at the opposite side of the bar. The collar is supplied with an adjusting screw 27 which holds it in a fixed position on the 95 shaft.

28 is a disk slid on the squared enlargement 24 of the shaft, and 29 is a circular saw blade carried also by the enlargement and secured to the disk by releasable bolts 30. 90

31 is a washer on the shaft and adjoining the outer face of the saw blade, and 32 is a chain wheel having a squared center slipped on the enlargement 24 and held in position thereon by a removable nut 33 screwed on to 95 the threaded end of the shaft. It will be seen that this construction is such that the disk with the saw can be removed from the shaft by removing the nut 33, and further that the saw blade can be taken from the 100 disk by unfastening the bolts 30. However when the saw is in use this saw blade can be termed permanent, that is, it is not adjustable on the shaft.

34 is a second adjustable saw blade 105 fastened by removable bolts 35 to a second disk 36 carried by the shaft, which disk is supplied with a sleeve 37 carrying an ad-

justing screw 38 which engages with the shaft and allows the disk with the saw to be adjusted thereon.

39 is a chain connecting the chain wheel 5 32 with the chain wheel 14.

When one is using the saw for making parallel cuts it is only necessary to adjust the saw blade 34 by loosening and again tightening the adjusting screw 38 on the 10 shaft, and then set the bar to whatever depth of cut it is required to make, the depth of the cut being indicated by the variable distance "a" (see Figs. 1 and 2) between the periphery of the saw blades and the 15 plate 21. When the wheel is rotated and the saw blades are applied to the work the cut is made. It is particularly pointed out that once the saw blades have reached the depth of the cut the disks 28 and 36 will advance 20 the saw as they rotate, it being noticed that the faces of the disks are roughened to insure a grip. If one desires to make a single cut the adjusting screw 38 is loosened and

the saw blade 34 is removed from the shaft. I have particularly designed the saw so that both the saw blades and the disks can be readily removed, thereby allowing others of different sizes to be substituted. The collar 26 prevents the shaft from end play and is removable to allow the shaft to be with- 30 drawn from the bar.

What I claim as my invention is:—

A hand saw comprising a frame, a shaft 35 rotatably supported on the extremity of the frame, a notched disk rotatable with said shaft, a rotary saw blade secured to said disk, means for rotating said saw blade, said disk being adapted to engage the work when the saw has cut a predetermined depth thus causing said blade to advance. 40

Signed at Winnipeg, this 29th day of November, 1911.

JOHN THOMAS.

In the presence of—

G. S. RONBURGH,
J. K. ELKIN.
